[57] CLAIM

The ornamental design for a golf putter grip, as shown and described.

DESCRIPTION

FIG. 1 is an isometric view of a golf putter grip showing my new design;

FIG. 2 is a front elevational view;

FIG. 3 is a right side elevational view;

FIG. 4 is a rear elevational view;

FIG. 5 is a left side elevational view;

FIG. 6 is a top plan view;

FIG. 7 is a bottom plan view; and,

FIG. 8 is a isometric view of a second embodiment of a putter grip shown in FIG. 1.

The broken line showing of hand placement on FIG. 2 is for illustrative purposes only and forms no part of the claimed design.

FIG. 1
